BOTTLE CLOSURE

Edgeworth Greene, Upper Montclair, N. J., assignor to Inter-Seal Corporation, New York, N. Y., a corporation of New York

Application March 16, 1937, Serial No. 131,123
Renewed June 22, 1939

8 Claims. (Cl. 215—22)

This invention relates to bottle closures of the difficultly refillable type, such as exhibited in Letters Patent Nos. 2,001,609 and 2,070,594, and 2,096,426.

5 The principal object of the invention is to improve the construction of such devices, particularly in respect of the so-called guard and weight and their structural and functional relations to each other; so that while a bottle equipped with 10 such a device may be properly sensitive to gravity in resisting attempts to refill it as by submerging the bottle in a horizontal position, yet the bottle will pour freely and promptly when held at a desirably small angle to the horizontal.

15 In the accompanying drawing,

Fig. 1 is a vertical section of a portion of a bottle neck, with a stopper embodying a form of the present invention applied thereto;

20 Fig. 2 is a bottom plan view of the guard member of Fig. 1;

Fig. 3 is a view similar to Fig. 1 illustrating certain modifications of structure in respect not only of the guard member but also of the weight member and of the valve member;

25 Fig. 4 is a bottom plan view of the guard member of Fig. 3;

Fig. 5 is a vertical central section illustrating a modification of what is shown in Fig. 3, particularly in that the Fig. 5 embodiment includes two 30 weight members and two valve members, as distinguished from the single valve and weight of the Fig. 3 construction; and

Fig. 6 is a bottom plan view of the guard member of Fig. 5.

35 Referring to the numerals on the drawing, the structure shown in Fig. 1 is in general similar to what is shown in Patent No. 2,096,426. There is a closure member 8 orificed at 9, with a cork or similar seal 10 for the orifice, a ferrule 11 for securing the assembly to the top of the bottle 29, and a cap 12 which must be destroyed before the cork 10 can be removed. These parts are generally as shown in Patent No. 2,096,426. As shown in that application also, there is a guard member 40 whose function is to prevent tampering with the valve parts, and this guard member, indicated by the reference character 14, is provided with three spaced lugs, shown clearly in Fig. 2, said lugs having portions 15 fitting into appropriate recesses in the cover member 8, and other portions 16 which are to extend downwardly into valve casing 17. By preference, the cover member 8 and the guard member 14 are made of porcelain, and the guard member is held in the Fig. 1 position by the introduction of glazing material be-

tween the lug portions 15 and the contiguous surfaces of the cover member, so that upon subsequent firing the guard member and the cover member become substantially one piece.

The casing 17 has a valve opening 18 for the 5 passage of liquid from the bottle into the casing, and there is a valve seat interiorly of the casing surrounding the opening 18 and controlled by a disc-like valve member 19 of buoyant material, such as cork, which is adapted to control the 10 opening 18. Cooperating with the buoyant valve member 19 in accordance with principles which are explained in my patents and aforesaid application there is a weight member 20 that is 15 movable to control and determine the movement of the valve member 19 towards and away from the opening 18 in accordance with various conditions of operation to which the bottle may be subjected. The guard member 14 is provided with a centrally located projection 21 that extends 20 downwardly from its lower face in the direction of the valve opening 18, and this extension 21 for a portion of its length rearwardly from its outer end takes the form of a frustum of a cone whose axis is the axis of the closure fitment and bottle, and whose sides show an inclination of about 20° to such axis. The weight member 20 is of generally circular form with an opening 25 centrally therethrough, the opening being so formed that its bounding walls define the frustum 30 of a cone symmetrical with that which is formed on the guard extension 21.

The operation of a device such as described is in general similar to what I have set forth, for example, in my said co-pending application Serial 35 No. 52,300. With the bottle in the position shown in Fig. 1 the weight 20 maintains the valve disc 19 in valve-closing position. If the bottle is inverted to proper discharge position the weight moves towards the discharge end of the bottle, carrying 40 the valve disc with it. If, the bottle having been emptied, it should be attempted to refill it by placing it on its side in a vessel containing liquid, it will be found that in bringing the bottle to the horizontal position (i. e., the position at right 45 angles to the Fig. 1 position, or thereabouts), movement of the weight 20 will have taken place in a direction away from the guard member 14 and towards the valve opening 18, this movement forcing the valve disc 19 into the Fig. 1 50 position. Such movement of the weight member is due to the fact that the weight member will have assumed the position indicated in dotted lines in Fig. 1, hanging as it were on the line of contact between the vertically upper coned sur- 55

faces of the guard extension 21 and of the weight opening, and the weight of the weight member and the cone angles will have caused a relative sliding movement between the guard extension 5 and the weight in the direction towards the valve opening 18, whereby the valve disc sliding along the ribs 33 of casing 17 is caused to effectively close said opening as shown.

For the more effective operation of the parts 10 it is desirable that the weight when moving from the full line position of Fig. 1 to the dotted line position under the conditions stated, should not tilt on the guard extension, that is to say, the cone surfaces of the weight member should 15 maintain a line contact with the upper surface of the cone extension of the guard throughout the extent of the movement of the weight towards the valve seat, with the result that the faces of the valve disc and the flat face of the 20 weight member which is in contact with the upper face of the valve disc are at all times substantially perpendicular to the axis of the cones, thereby insuring more prompt and effective closure of the valve opening. This result is 25 brought about by a proper distribution of the mass of the weight member, so that throughout the movement of the weight member from the wide-open position of the valve disc 19 to the fully closed position thereof as in Fig. 1, the center 30 of gravity of the weight member will coincide with a line passing through the contacting surfaces of weight and guard extension, and preferably so that this line will never quite reach the outer end of the cone extension of the guard. 35 Thus it will be noted that the overall diameter of the relatively short weight of Fig. 1 for a considerable part of its length nearest the guard is definitely larger than that of the part nearest the valve disc.

40 In order to prevent adhesion between guard and weight the latter may be provided with three upstanding spaced lugs 32. While I have shown the weight member provided with a through opening (and this construction has some advantages), I contemplate as an alternative that the reduced end of the opening may be closed. Also 45 either the cone extension or the coned opening may be provided with longitudinal anti-friction guide ribs similar to the ribs 33 on the inner wall of valve casing 17.

50 Referring now to Fig. 3, the structure there shown is in general similar to what has already been described, except that the guard member is provided, in addition to the coned extension 55 21, with a reduced cylindrical portion 23 that continues beyond the lower end of the cone extension. The buoyant valve member in this embodiment is provided with a thimble 25 set into a central opening in the valve disc, the closed bottom of the thimble generally extending below 60 the plane of the lower face of the disc, and the upper end of the thimble being slightly flared outwardly and preferably extending not above the upper face of the valve disc. Into this thimble the cylindrical extension 23 projects.

65 The action of this embodiment insofar as the relation between guard, weight and valve disc is concerned, is similar to that already described with reference to the Fig. 1 embodiment except 70 that the valve slides along the extension 23 instead of on the ribs 33 which have been obviously omitted. If desired, the valve casing 26 of the Fig. 3 embodiment, instead of extending up into the cover member 8, as in Fig. 1, may have an outwardly projecting flange 27 which engages

a gasket 28 on top of the mouth of the bottle 29, and the orificed cover member 30 may be designed to rest upon this flange 27, a gasket 31 being interposed as shown. In this embodiment also it is not essential that the guard member should be permanently united with the cover member 30, since the assembly of the guard member with the cover member may be accomplished by means of the gasket 31 as shown, the inner edge portion of the gasket engaging beneath lugs 34 and preferably having a snug fit around the sides of lug portions 35. A ferrule will be used to hold the assembly on the bottle, as in Fig. 5.

In the Fig. 5 construction the closure member 36 and the valve casing 37 are in general as shown in Fig. 3. The interior of the closure member 36 is provided with a plurality of spaced longitudinal ribs 38, against the lower ends of which abuts a wheel-like member 39 (see Fig. 20 6). The member 39 is shouldered as indicated at 40, and a gasket 41 is frictionally held against this shoulder, said gasket extending outwardly and forming the seal between the closure member 36 and the valve casing 37. The hub of the 25 wheel 39 is extended downwardly to form a cone extension 50, and there is a through opening 42 extending through this hub. 43 is a weight member similar to that shown in Fig. 3, and 44 is a valve disc similar to that shown in Fig. 3. 30 45 is a rod-like member which extends through the wheel 39 and the cone extension thereof and down into the central well of the valve disc. The upper end of this rod 45 extends well above the wheel 39 and has fastened on it a guard 35 piece 46, the upper surface of which has a plurality of radial ribs 47 to direct the flow of liquid which, entering through the opening 18, passes around the valve disc and through the spaces between the spokes of the wheel and between the ribs 38 and out through the discharge opening 48. There is a second valve disc 49 carried by the upper end of the rod 45 and movable with the rod 45 and the guard piece 46. This valve disc in the Fig. 5 position covers the openings between the spokes of the wheel member 39 and of course when the valve disc 49 is in the Fig. 5 position the valve disc 44 will also be closed as shown. The cone extension 50 and the cone opening in the weight member are 40 provided for the same reasons as already set forth in connection with the description of the Fig. 1 and Fig. 3 embodiments and with the same results so far as making it difficult to fill the bottle when it is laid on its side in a vessel 45 of liquid.

The weight members of Figs. 3 and 5 are relatively long as distinguished from the weight of Fig. 1 so that a line passing through the center of gravity in either case will not quite reach the extreme ends of the conical portions of guard members 21 (or 50) when the bottle is horizontally disposed and the weight is in valve-closing position.

It should be noted in Fig. 1 that part 21 is 6 cylindrical above its conical portion to thus reduce the length of the line of contact between weight and guard, in order to reduce friction to a minimum. The same is true of the corresponding parts shown in Figs. 3 and 5.

It should also be noted that in order to get a 7 long weight so that the center of gravity will be short of the end of the cone on the stem, and without adding to depth of valve casing 26 and 31, the spokes of the wheel 39 in the Fig. 5 con-

struction have been cut back from the lower face thereof, and the bottom of the guard of the Fig. 3 construction has been raised above the ends 35 of ribs 34. These arrangements permit the use of a maximum length weight without increase in the depth of the valve casing, and without undesirably limiting the travel of the valve disc away from the valve seat.

I claim:

- 10 1. In a bottle stopper for attachment to a bottle to render the same non-refillable a valve casing having an inlet opening and having therein a valve member, a substantially centrally disposed stem and a weight freely slidably mounted 15 on the stem, said stem and weight having surfaces inclined at substantially the same angle to the axes thereof and of such relative diameters in cross section that the surfaces can meet only in a single substantially longitudinal line of contact, the center of gravity of said weight being 20 so located and the angle of inclination of said surfaces being such that the weight is actuated by gravity toward the valve seat when the bottle is in a horizontal position.
- 25 2. In a bottle stopper for attachment to a bottle to render the same non-refillable a valve casing having an inlet opening and having therein a valve member, a substantially centrally disposed stem and a weight freely slidably mounted on 30 the stem, said weight having a through opening, said valve member having a substantially centrally disposed orifice, said stem having a rod-like portion passing through said weight into said valve member orifice and having a portion provided with a surface circular in cross section and inclined at an angle to the axis of the stem, a part of the wall of the through opening of said weight being inclined at substantially the same angle as the inclined surface of the stem and 35 being of such diameter relative to the stem that the inclined surfaces can contact only substantially longitudinally linearly whereby the weight is actuated by gravity toward the valve seat when the bottle is in a horizontal position.
- 40 3. In a bottle stopper for attachment to a bottle to render the same non-refillable a valve casing having an inlet opening and having therein a valve member, a substantially centrally disposed stem and a weight freely slidably mounted on 45 the stem, said weight having a through opening, said valve member having a substantially centrally disposed orifice, said stem having a rod-like portion passing through said weight into said valve member orifice and having a portion provided with a surface circular in cross section and inclined at an angle to the axis of the stem, a part of the wall of the through opening of said weight being inclined at substantially the same angle as the inclined surface of the stem and 50 being of such diameter relative to the stem that the inclined surfaces can contact only substantially longitudinally linearly whereby the weight is actuated by gravity toward the valve seat in this position.
- 45 4. In a bottle stopper for attachment to a bottle to render the same non-refillable a valve casing having an inlet opening and having therein a valve member, a substantially centrally disposed stem and a weight freely slidably mounted

on the stem, said weight having a through opening, said valve member having a substantially centrally disposed orifice, a rod-like secondary valve-actuating member passing through stem and said weight into said valve member orifice, 5 said stem having a portion provided with a surface circular in cross section and inclined at an angle to the axis of the stem, a part of the wall of the through opening of said weight being inclined at substantially the same angle as the inclined surface of the stem and being of such diameter relative to the stem that the inclined surfaces can contact only substantially longitudinally linearly whereby the weight is actuated by gravity toward the valve seat when the 10 bottle is in a horizontal position.

5. In a bottle stopper for attachment to a bottle to render the same non-refillable a valve casing having an inlet opening and having therein a valve member, a substantially centrally disposed stem and a weight freely slidably mounted on the stem, said weight having a through opening, said valve member having a substantially centrally disposed orifice, a rod-like secondary valve-actuating member passing through said 15 stem and said weight into said valve member orifice, said stem having a portion provided with a surface circular in cross section and inclined at an angle to the axis of the stem, a part of the wall of the through opening of said weight being 20 inclined at substantially the same angle as the inclined surface of the stem and being of such diameter relative to the stem that the inclined surfaces can contact only substantially longitudinally linearly whereby the weight is actuated by gravity toward the valve seat when the 25 bottle is in a horizontal position.

6. In a bottle stopper for attachment to a bottle to render the same non-refillable, a valve casing having an inlet opening and having therein a valve member, a substantially centrally disposed stem and a weight freely slidably mounted on the stem, said stem and weight having co-operating surfaces inclined longitudinally, said 30 surfaces being so proportioned that adjacent parts thereof can meet only in a single substantially longitudinal line of contact when the bottle is in a horizontal position whereby the weight will be actuated by gravity toward the valve seat in 35 this position.

7. The device set forth in claim 6, in which the weight has a through opening and the inclined surface of the stem slides on the inclined surface of the through opening.

8. In a bottle stopper for attachment to a bottle to render the same non-refillable, a valve casing having an inlet opening and having therein a valve member, a substantially centrally disposed stem and a weight freely slidably mounted on the stem, said stem and weight having co-operating surfaces inclined longitudinally, said surfaces being so proportioned that adjacent parts thereof can meet only in a single substantially longitudinal line of contact when the bottle is in a horizontal position and said weight having its center of gravity so located that the weight will be actuated by gravity toward the valve seat in 50 this position.
